CRANE HOIST CONTROL

Glenn E. Stoltz, Pittsburgh, Pa., assignor to Westinghouse Electric & Manufacturing Company, East Pittsburgh, Pa., a corporation of Pennsylvania

Application May 16, 1939, Serial No. 273,851

9 Claims. (Cl. 172—179)

My invention relates to a control system for an electric motor and is particularly applicable to a motor utilized for operating load hoisting or elevating devices or load lowering devices such as cranes and the like.

An object of my invention is to provide a system or control that embodies a minimum number of units and which is simple and reliable in operation, and is inexpensive to manufacture.

10 Another object of my invention is to provide a control system which has substantially ideal or most desirable speed torque curves for a hoist motor when operating in the lowering direction.

15 A more specific object of my invention is to provide a motor-generator set used as a booster to boost the field strength of the main motor when the main motor is regenerating current due to an overhauling load in the lowering direction and, in effect, is acting as a generator and which 20 motor generator is inoperative when the main or hoist motor is acting as a motor either in the lowering or hoisting operation.

25 Other objects and advantages will become more apparent from a study of the following specification when considered in conjunction with the accompanying drawings, in which:

Fig. 1 is a diagrammatic showing of a complete system of control embodying my invention;

30 Fig. 2 shows the motor circuit for the fifth controller position of hoisting;

Fig. 3 shows the motor circuit for the fifth controller position during the lowering operation;

35 Fig. 4 shows a series of samples of speed torque curves for control systems conventional in the art for all the controller positions of the motor when the motor is operating in the lowering direction; and

40 Fig. 5 is a sequence chart showing the sequence of operation in the various switches in the motor circuits both for the hoisting and the lowering operation.

45 In a crane hoist control it is desirable to obtain as high a speed as possible for the crane hook when lowering empty, and at the same time not obtain an excessive speed when lowering with a heavy load. Referring to the speed torque curves in Fig. 4, which are illustrative of control systems when the load is overhauling, the hoist motor is used to develop a braking torque, the figure showing that with 63% field current the increase in speed with load is appreciable but not dangerous. The figure also shows the performance of the motor in one instance 50 with 37% field current and another with 24%

field current, where with less than full load on the hook, the hoist motor would run away.

In accordance with my invention the above mentioned runaway condition will be eliminated and the speed torque curves for low values of 5 field current will be substantially flattened, very much like those illustrating 44% and 63% field current.

Referring more particularly to Figure 1 of the drawings, M designates a hoist motor (of the 10 series type), which is to be controlled and B and F, respectively, designate the brake winding and field winding. M' and G' designate the units of the motor-generator set, which set is used as a booster. Associated with the motor of the 15 motor-generator set is a field coil 20 and a conventional control rheostat 21. The generator G' of the motor-generator set has a field winding 22, a conventional control rheostat 23 and a rectifier unit, preferably of the copper oxide 20 type, 24, all of which are connected in shunt across a resistance R, which resistance is permanently in series with the armature of motor M. Since it will be logical to place the motor-generator set used as a booster on or near the crane 25 cab with the control, resistance R is installed in the lead of the armature of the hoist motor, from which will be shunted current to excite the field 22 of the booster generator G'. The voltage of the generator should then be proportional to 30 the loads taken by the armature up to the point where the field of the booster saturates. It is not essential that the booster voltage be directly proportional to the armature current of the hoist motor, but it will be necessary to design the 35 booster so that it does not saturate at too low a load. The rectifier unit 24 is placed in the field circuit of the booster generator so that current will flow in the field of the booster generator only when the load is heavy enough to cause the hoist 40 armature to regenerate and, in effect, act as a generator. When the hoist armature is being accelerated or when the load is so low that the hoist motor is operating as a motor, the flow 45 of current will be in the opposite direction and the rectifier unit 24 will prevent any current flow in the field 22 of the booster so that the booster will have no modifying effect on the field of the main motor when the latter is acting as a motor 50 in the lowering direction.

Since this booster effect of the crane motor field is only wanted in the lowering direction, the armature of the booster will be connected in the field circuit of the hoist motor in such a manner 55

that it will be in the circuit only during the lowering direction.

A control system is illustrated for the motor and is shown in the deenergized position. A controller C which may be of any desirable type such as the drum type and has a plurality of contact segments for varying the circuit connections for different positions in the hoisting or lowering direction. Five positions are shown in the hoisting direction and five positions are also shown in the lowering direction for giving various values of speed and torque to the motor in these directions. Contact members 1 to 11, inclusive, and 16 (and 16c) are operable by relays 1A to 11A, inclusive, 5 and 16A respectively to secure various circuit combinations in the hoisting and lowering directions. Contact members 12 and 12c, 13, 14 and 15, inclusive, are operable by time limit relays 12A to 15A, inclusive, respectively. The time limit relays 12A to 15A, inclusive, have main coils 12M to 15M, inclusive, and neutralizing coils 12N to 15N, inclusive, respectively. Each of these relays is biased in one direction by a spring as shown. A relay rheostat 26 is provided for adjusting a time 10 constant of the relays. It will be noted that the springs associated with each of the relays is also adjustable thereby providing additional adjustability of the time constant of the relays. The operation of these time limit relays forms no part of 15 my invention, but to briefly describe their operation it may be generally stated that relay 12A holds one of its associated contact members 12 closed in the lowering operation, due to the time 20 delay of coil 12N, long enough to insure release of the brake by maintaining relay 5A energized to close contact members 5, and prevents closing of contact members 18 in the lowering direction until contact members 12 are open. Time limit relay 13A picks up on the fourth point lowering and 25 holds its contact members 13 closed thereby completing a circuit to energize coil 6A and close contact members 18 to insure energization of relay 11A which closes contact members 11 to provide a regular braking circuit, and to open contact 30 members 6 to prevent application of the emergency braking circuit for a fraction of a second if the master switch is returned suddenly to the "off" position.

By referring to Fig. 5, which is a sequence chart 35 showing the sequence of operation of the various switches in the motor circuits for both hoisting and lowering operations, the particular circuit for any of the five positions of hoisting or lowering can be identified. Inasmuch as my invention is not concerned with the successive steps or positions in the operation of the motor either in the hoisting or in the lowering direction, it is deemed 40 that a detailed explanation of each successive position in hoisting or lowering is unnecessary. Furthermore, the control system illustrated in the figures together with the sequence chart in Fig. 5 will readily disclose to those familiar with the art what the various circuit in each successive position in hoisting or lowering consists of. 45 It is felt that a detailed explanation of each step would be not only superfluous but would tend to confuse the reader as to the essence of the invention. However, to briefly summarize the successive operations in both hoisting and lowering operation, it may be stated that in all five positions of hoisting, the motor-generator booster is inoperative since it is omitted from the circuit and all of the field coils together with the braking field coil are connected in series with the incoming power line, hence the motor operates as a 50

series motor. Fig. 2 shows the fifth position of hoisting and is illustrative of this series connection. On the other hand, on all five positions of lowering, the motor generator set M', G', together with its associated parts, is included in the circuit. Furthermore, on all five positions of lowering, the field coil F and the brake coil B are connected in parallel with the motor armature M so that the motor is now acting as a shunt motor. Fig. 3 which shows the fifth position of lowering 5 is illustrative of the shunt connection. In the hoisting operation the full value of starting resistance is connected in series with the various field coils, brake coil and motor armature and, in general, in going through the five successive steps, the starting resistance is gradually shunted out by successive increments until finally, as shown in Fig. 2 representing the fifth hoisting position, the starting resistance is completely shunted out and the motor with its various field 10 coils and brake coil is connected directly across the line. On the other hand, in the lower operation in going from the first to the fifth position, resistance is gradually inserted in series with the shunt field in successively greater amounts until 15 finally, as will be noted from Fig. 3 illustrating the fifth lowering position, the full value of resistance is inserted in series with the shunt field. As it will be obvious to those skilled in the electrical art, as the resistance is gradually decreased 20 in going from the first to the fifth position in the hoisting operation of a constant load when the motor M is connected as a series motor, the speed and torque thereof will gradually increase. On 25 the other hand, in the lowering operation, as the resistance in series with the shunt field is gradually increased so as to gradually weaken the shunt field, the speed of the motor gradually increases and the torque decreases.

My invention is specifically directed to the 30 use of a booster motor-generator set in the lowering operation of the main hoist motor. When light loads are lowered and the main motor is acting as a motor, no shunt current will traverse the field coil 22, because of the blocking action 35 of rectifier 24. However, on heavier loads in the lowering direction, which are sufficient to cause the motor to overhaul and regenerate current in the opposite direction of the normal motor current, a shunt current will flow through the generator field coil 22 in an opposite direction and will no longer be arrested by rectifier 24, and this boosting current will strengthen the main field F to such an extent as to cause the speed 40 to increase less rapidly with increasing loads, or 45 to remain substantially constant or even decrease, depending on the ampere turns of field coil 22.

These characteristics will become more apparent in tracing the circuit. When light loads 50 are lowered and the main motor M is acting as a motor, the main circuit may be traced, in Figs. 1 and 3, from the terminal marked (+), through bridged contact members 2, motor M, resistor R, bridged contact members 7, 9 and 8, respectively, to the negative terminal marked (-). Connected 55 in parallel to resistor R is another circuit including rheostat 23, field coil 22 (of generator G' of the booster motor-generator set) and rectifier 24. However, inasmuch as the flow of current is of from left to right through resistor 60 R, the rectifier 24 will arrest current flow through the parallel path. However, if a load is being lowered that is sufficiently heavy so as to cause motor M to overhaul, then current will be regenerated by motor M in the above traced main 65 circuit.

circuit but in an opposite direction due to the fact that the motor M is now acting, in effect, as a generator. Inasmuch as this regenerated current may be greater than the normal flow of supply current (previously traced) but opposite in direction, the resultant current will flow through resistance R in a direction from right to left. Now current will flow through the parallel path including rectifier 24, booster generator field coil 22 and rheostat 23 due to the manner in which rectifier 24 is connected, as the result of which generator G' will start to generate a voltage in the direction indicated by the arrow. A main shunt path may now be traced from the terminal marked (+) through bridged contact members 2, field coil F, brake coil B, resistors R₂ and R₃, the armature of generator G', bridged contact members 16c, 11, 9 and 8 successively to the negative terminal (-). It will thus be seen that as the current regenerated by motor M increases, the current through field winding 22 increases and the voltage developed across the armature of generator G' increases therefore boosting the current flow through the main shunt path (i. e., through field coil F) hence tending to decrease the speed of motor M. It will be noted that the main shunt path is the same during lowering light loads during which motor M is acting as a motor, that is, it includes the armature of generator G', however, since no voltage is developed across this armature (since no current is flowing through the field coil 22 due to the arresting action of rectifier 24) no additional current will be sent through the main shunt circuit through field coil F, hence there will be no modifying or boosting action on field coil F.

While I have described the motor generator set as being in the circuit in all positions of lowering, it will be obvious that it is also possible, instead, to have the motor-generator set in circuit only in a few of the ultimate positions of lowering, say for example, in the fourth and fifth positions only of lowering. In other words, it is recognized that the most important use of the booster is in the latter positions or the last position of lowering. The necessary change in the circuit connections for accomplishing this will be obvious to those skilled in the art. Also, if the booster is put in other than the fifth point such as the fourth or third, its effect can be decreased. This will be partially automatic as the motor field approaches saturation. While this alternate arrangement is recognized, it is felt that the preferable and most simple circuit connection would be that as previously described, since a minimum number of contactors is used, that is, the arrangement by which the motor-generator is kept in circuit throughout the entire lowering operation.

On cranes it is desirable only to prevent the load and motor from running away under heavy loads, the value of the booster can be selected to keep the speed torque curves flat, approximately as shown in Fig. 4 for 63% and 44% field amperes. On other applications where it may be desirable to have a lower speed load condition than with empty hook, the value of the booster can be increased so that the speed torque curves drop off with increased loads.

My control system is a substantial improvement over the well known control systems employing relays and the like wherein abrupt changes are secured for the purpose of checking excessively high speed but which abrupt changes

are detrimental to safe operation of a crane hoist. Obviously any sudden change in the speed of the crane either in the raising or lowering position might cause a shaking off of the load which would be highly dangerous and at the same time the control of the crane would be very confusing and difficult.

Many protective features usually embodied in control systems of this kind such as an overload and undervoltage protection have been omitted for the sake of simplicity, but it is understood, of course, that these features may be incorporated in the above described control system.

I am, of course, aware that others, particularly after having had the benefit of the teachings of my invention, may devise other devices embodying my invention, and I, therefore, do not wish to be limited to the specific showings made in the drawings and the descriptive disclosure hereinbefore made, but wish to be limited only by the scope of the appended claims and such prior art that may be pertinent.

I claim as my invention:

1. A control system for a hoist motor comprising, in combination, a hoist motor, circuit means for energizing said motor to effect a hoisting or lowering operation, means effective only during the overhauling lowering operation of said motor and not the hoisting operation thereof for continuously and directly compensating the field strength of said motor as a function of the load current of the motor to effect slowing down of said motor.

2. A control system for a hoist motor comprising, in combination, a hoist motor, circuit means for energizing said motor to effect a hoisting or lowering operation, means effective only during the overhauling lowering operation of said motor and not the hoisting operation thereof for continuously and directly boosting the field strength of said motor in accordance with the load of said motor to effect slowing down of said motor.

3. A control system for a hoist motor comprising, in combination, a hoist motor, circuit means for energizing said motor to effect a hoisting or lowering operation, said motor, having a field coil which is connected in shunt therewith during lowering operation of the motor, a booster generator which is effective during the lowering operation only, of said motor for boosting the field strength thereof and for effecting slowing down of said motor.

4. A control system for a hoist motor for a crane or the like comprising, in combination, a hoist motor including a field coil, circuit means for energizing said motor to effect either a hoisting or lowering operation, a booster generator having a field coil which is effective to compensate said motor field coil and which is in circuit relation with the armature of said motor so that the voltage impressed on said booster generator field coil is proportional to the load current flowing through the armature of said hoist motor.

5. A control system for a hoist motor for a crane or the like comprising, in combination, a hoist motor, including a field coil circuit means for energizing said motor to effect either a hoisting or lowering operation, a booster generator having a field coil which during at least a part of the lowering operation, only, of said motor is in circuit relation with the armature of said motor so that the voltage impressed on said booster generator field coil is proportional to the load current flowing through the armature of said

5 hoist motor, rectifier means in circuit relation with said field coil which allows current flow only in the direction of flow of regenerated current developed in said armature due to an overhauling load, and which is not conductive to current flowing through said armature when said motor is operating as a motor.

6. A control system for a hoist motor for a crane or the like comprising, in combination, a 10 hoist motor including a field coil, circuit means for energizing said motor to effect either a hoisting or lowering operation, a booster generator having a field coil which during the entire lowering operation, only, of said motor is in circuit 15 relation with the armature of said motor so that the voltage impressed on said booster generator field coil is proportional to the load current flowing through the armature of said hoist motor, rectifier means in series with said field coil which 20 allows current flow only in the direction of flow of regenerated current developed as the result of generator action of said motor during an overhauling load, and which is not conductive to current flow through said armature when said 25 motor is operating as a motor.

7. A control system for a hoist motor for a crane or the like comprising, in combination, a hoist motor including a field coil, circuit means 30 for energizing said motor, to effect either a hoisting or lowering operation, a resistor, which may be a series winding or lead of the hoist motor armature in series with the armature of said motor, a motor-generator booster set having a generator field, rectifier means connected in series 35 relationship with said booster generator field and said rectifier means and booster generator field being connected in shunt with said resistor, said motor-generator booster set being operable to compensate the field coil of said hoist motor only 40 during lowering operation of said motor, said rectifier means allowing flow of current developed by regeneration of said motor due to its generator action during overhauling loads and impeding the flow of motor current in said armature when 45 said motor is acting as a motor.

8. A control system for a hoist motor for a

5 crane, derrick or the like comprising, in combination, a hoist motor including a field coil, circuit means for energizing said motor, to effect either a hoisting or lowering operation, a resistor in series with the armature of said motor, a motor-generator booster set having a generator field, rectifier means connected in series relationship with said booster generator field, and said rectifier means and booster generator field being connected in shunt with said resistor, said motor-generator booster set being operable to compensate the field coil of said hoist motor only during lowering operation of said motor and during at least a part of said lowering operation, said rectifier means allowing flow of current developed 15 by regeneration of said motor due to its generator action during overhauling loads in the lowering direction and impeding the flow of motor current in said armature when said motor is acting 20 as a motor.

9. A control system for a hoist motor for a crane or the like comprising, in combination, a hoist motor including a field coil, circuit means 25 for energizing said motor, to effect either a hoisting or lowering operation, a resistor in series with the armature of said motor, a motor-generator booster set having a generator field, rectifier means connected in series relationship with said booster generator field, and said rectifier means and booster generator field being connected in 30 shunt with said resistor, said motor-generator booster set being operable to compensate the field coil of said hoist motor only during lowering operation of said motor, said rectifier means allowing flow of current developed by regeneration of 35 said motor due to its generator action during overhauling loads and impeding the flow of current in the booster field when said motor is acting as a motor, said hoist motor including a field coil which is connected in series relation with 40 said booster armature thereof during lowering operation, said booster generator being effective during lowering operation with an overhauling load to increase the field strength of said hoist motor field thereby slowing down said motor.

45 GLENN E. STOLTZ.
